United States Patent Office.

W. S. SHOEMAKER, OF TOWSONTOWN, MARYLAND, AND E. H. SHOEMAKER, OF LANCASTER, OHIO.

Letters Patent No. 90,028, dated May 11, 1869.

IMPROVEMENT IN HOG-RING.

The Schedule referred to in these Letters Patent and making part of the same.

To all whom it may concern:

Be it known that we, W. S. SHOEMAKER, of Towsontown, in the county of Baltimore, and State of Maryland, and E. H. SHOEMAKER, of Lancaster, in the county of Fairfield, and State of Ohio, have invented a new and improved Hog-Ring; and we do hereby declare that the following is a full, clear, and exact description thereof, reference being had to the accompanying drawings, making part of this specification, in which—

Figure 1 shows the manner of applying the improved device to the snout of a hog.

Figure 2 is a front view of the device.

Figure 3 is a central section through the device.

This invention relates to a new and useful improvement on devices which are designed for preventing hogs from rooting.

It consists of a wire bent in the form of a ring, with the ends turned outwardly and brought together; and after being inserted through the snout of a hog, these ends are passed through cuts made through a plate, and bent in such manner that a permanent fastening is secured, as will be hereinafter explained.

The objection to devices hitherto employed for preventing hogs from rooting, and which it is the object of our invention to remedy, is that the animals work off the devices, or bend or break them, so that they fail to serve the purpose required of them.

The following description will enable others to understand how to make and use our improved device.

We take a wire rod of proper diameter and strength, and bend it centrally so as to form the ring a with the two ends a^1 a^1 , extending outwardly, and pointed if desired.

We then take a piece of sheet-metal of proper size and shape, represented by b in the drawings, and make three parallel cuts through it, and press out the intermediate cut portions in opposite directions, so as to form loops c , for receiving through them the straight portions a^1 , of the wire, which portions we term the locking-tongue of the ring.

To apply the device, a hole is made through the nose or snout of a hog, and one of the straight portions a^1 of the tongue inserted into it, and drawn through until the ring a is in its place.

The two straight wires, a^1 a^1 , are then brought close together, and inserted through loop c on one side of the plate b , bent around the lower edge of this plate, inserted through the opposite loop c , and then bent backward, as shown at a^2 , thereby forming two hooks, which will prevent the plate b from slipping on the tongue of the ring, and will so effectually seal or lock the ring as to prevent any liability of its being worked off the snout of the hog.

Having described our invention,

What we claim as new, and desire to secure by Letters Patent, is—

A hog-ring, a , having a tongue, a^1 a^1 , formed by its ends bent as described, in combination with a looped seal-plate, b , substantially as described.
